UNITED STATES PATENT OFFICE.

JOHN L. STELLING, OF BROOKLYN, NEW YORK, ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed July 12, 1923. Serial No. 650,999.

To all whom it may concern:

Be it known that I, JOHN L. STELLING, a citizen of the United States, residing at Brooklyn, in the county of Kings, State of New York, have invented certain new and useful Improvements in Electron-Discharge Devices, of which the following is a full clear, concise, and exact description.

This invention relates to electron discharge devices, and more especially to vacuum tubes in which the electrodes are supported from a collar encircling the stem of the enclosing vessel.

The object of this invention is to insure a firm frictional contact between the collar and the stem, and is attained by roughening the surface of the glass with which the collar contacts.

Referring now to the drawings, the single figure is an elevation partially broken away of a vacuum tube embodying the invention.

The enclosing vessel 10 is provided with a re-entrant stem 11, the upper end 12 of which comprises a press in which are sealed the leading-in wires for the electrodes. A corrugated collar 13 surrounds the lower portion of the stem 11 and has extending therefrom integral arms 14, which terminate in corrugated anode plates 15. A block 16 of insulating material is supported by the

plates 15 at their ends and supports the other electrodes of the tube.

In order to insure a tight frictional contact between the collar 13 and the stem 11, the latter is roughened, as shown at 17. 35 This roughening may be accomplished in any desired manner, but is preferably attained by sand blasting the stem. Thus, when the collar 13, which is formed of a slightly smaller diameter than that of the 40 stem is forced on the stem and into contact with the portion 17, the frictional contact of the roughened surface with the collar 13 effectively prevents slippage of the collar and maintains it firmly in position. 45

What is claimed is:

1. In an electron discharge device, a glass support, a collar surrounding said support, the surface of the support in contact with the collar being roughened and an electrode supported by said collar. 50

2. In an electron discharge device, an enclosing vessel having a reentrant stem, a collar encircling said stem, the surface of the stem in contact with the collar being 55 sand blasted, and an electrode supported by said collar.

In witness whereof, I hereunto subscribe my name this 7th day of July, A. D. 1923.

JOHN L. STELLING.
